DESIGN FOR A VEILING

Samuel H. Aibel, New York, N. Y.

Application January 24, 1939, Serial No. 82,561

Term of patent 3½ years

To all whom it may concern:

Be it known that I, Samuel H. Aibel, a citizen of the United States of America, residing in the city of New York, county of New York and State of New York, have invented a new, original, and ornamental Design for a Veiling, of which the following is a specification, reference being had to the accompanying drawing, forming part thereof.

The figure on the drawing is a plan view of a veiling showing my new design.

I claim:

The ornamental design for a veiling, substantially as shown.

SAMUEL H. AIBEL.
